CHARLES F. SMITH, OF NEW BRITAIN, CONNECTICUT, ASSIGNOR TO LANDERS, FRARY & CLARK, OF NEW BRITAIN, CONNECTICUT, A CORPORATION OF CONNECTICUT.

ELECTRICAL ATTACHMENT PLUG.

Application filed March 18, 1926. Serial No. 95,732.

This invention relates to electrical attachment plugs of the type having a body portion provided with contact members connected to the ends of flexible conductors or cords, plugs of this sort being now in universal use for plugging in electrical devices, such as cooking utensils, electrical sad irons, and the like. Plugs of this sort give considerable trouble and require more or less frequent repair due to the fact that the connections between the wires and the terminals or contacts carried by the plug body are disturbed or broken by strains and jerks exerted on these connections. Not infrequently, one using the plug will carelessly pull or jerk on the conductor when it is desired to detach the plug from the utensil, and, when the plug is used in connection with a sad iron or similar article, the cord is subjected to sudden jerks whenever the iron is moved as far as the conductor will reach.

The aim of the present invention is to provide an improved and simple attachment plug wherein the connections between the conductors and the terminals within the plug are relieved of excessive strains in a very effective and economical manner.

In accordance with the present invention, the plug body is provided with passages for the respective connectors or cords, and these passages are provided with transversely extending ridges so arranged that the cords are bent more or less sharply over the same, with the result that, when a pulling force is exerted on the cords, the strain is more or less taken up by the ridges and, to that extent, the connections between the cords and the terminals are relieved. Preferably, the plug body is in two parts, and these parts are identical in all particulars, this being of advantage in that there is a considerable saving in manufacturing and carrying charges, it being possible to construct the parts of the plug body from the same molds and to furnish both parts from the same supply.

Other objects will be in part obvious and in part pointed out more in detail hereinafter.

The invention accordingly consists in the features of construction, combination of elements and arrangement of parts which will be exemplified in the construction herein-after set forth, and the scope of the appli-

cation of which will be indicated in the appended claims.

In the accompanying drawings, wherein I have shown, for illustrative purposes, one of the embodiments which the present invention may take:

Figure 1 is a perspective view looking at the inside surfaces of the two parts of the plug body, the parts being in the partially open position shown in Fig. 2;

Fig. 2 is an end view of the parts as shown in Fig. 1;

Fig. 3 is a plan view of one of the parts of the plug body;

Fig. 4 is a transverse sectional view through the assembled plug body, this view being taken substantially on line 4-4 of Fig. 3;

Fig. 5 is a view similar to Fig. 4 with the section taken on line 5-5 of Fig. 3;

Fig. 6 is a longitudinal sectional view through the assembled plug body, this view being taken substantially on line 6-6 of Fig. 3; and

Fig. 7 is a view of the complete attachment plug with a portion of one of the parts of the plug body broken away for purpose of illustration.

Referring to the drawings in detail, *a* and *b* designate the two parts of the plug body; *c*, *c*, the flexible connectors; *d*, *d*, the terminals, the latter being shown in dotted lines, as the particular construction thereof forms no part of the present invention; *e*, a spring connected to the plug and through which the connectors pass; and *f*, *f*, the usual bolts for securing together the two parts of the plug body.

The two parts *a* and *b* of the plug body are preferably identical in construction and, as they are so shown in the accompanying drawings, a description of one will apply to the other. Each of these parts has, in its inner face, a pair of recesses 10 adapted to accommodate the terminals *d*, and channels or grooves 11 and 12 leading from the respective recesses 10 to an opening 13 through which the cords lead into the plug body. The recesses 10 and the channels 11 and 12 are symmetrical with respect so the medial longitudinal line of the plug part 106 so that, when the parts are placed face to face, the channels register so as to form passages through which the cords *c* extend.

Each of the channels is preferably reversely curved longitudinally so as to make the passages more or less tortuous in the plane of the meeting faces of the parts. Each of the channels is provided with one or more transversely extending ridges or high spots and one or more hollows or depressions and, preferably, the ridge or ridges of the channel 11 is offset or staggeredly arranged with respect to the ridge or ridges of the channel 12. In the present illustrative disclosure of the invention, the channel 11 is provided with a transversely extending ridge 15 and a depression 16; and the channel 12 has a depression 17 transversely alined with respect to the ridge 15 and a ridge 18 transversely alined with respect to the depression 16.

When the two parts of the plug are placed face to face, as shown in Figs. 4, 5 and 6, the ridge 15 of the channel 11 of each part is opposed to the depression 17 of the channel 12 of the other part and similarly the respective ridges 18 and depressions 16 are opposed. The ridges 15 and 18 are so positioned and are of such size that they give to the cords a series of more or less pronounced bends, as shown more clearly in Fig. 6. When a pulling force is exerted between the cords and the plug, the resultant pressure between the cords and the ridges takes up a very considerable part of the pulling strain, thereby relieving the connections between the cords and the terminals. It will thus be observed that the cords are held in place in such manner that the connections between the cords and the terminals are greatly relieved of any pulling strains without the objectionable use of separate clamping devices or knots.

Since the parts of the plug body are identical in all respects to one another, these parts may be made from the same mold, and it is not necessary to manufacture or carry in stock two parts of different construction in order to make up the plug body, which means that there is a decided saving in manufacturing and carrying charges. Also, since the two parts are identical, and when placed face to face upon one another the channels must properly register with the ridges in the desired relation, no confusion or error can result in assembly, and the act of assembling the parts is greatly facilitated.

As many changes could be made in the above construction and many apparently widely different embodiments of this invention could be made without departing from the scope thereof, it is intended that all matter contained in the above description or shown in the accompanying drawing shall be

interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In an electrical attachment plug, a body portion formed of two like parts identical in size and shape, each of said parts having a pair of symmetrically positioned channels and each channel having therein a transversely extending ridge which ridges are out of line transversely to each other, whereby when said parts are assembled, the ridges in the registering channels are offset and longitudinally spaced from each other.

2. In an electrical attachment plug, a body portion formed of two like parts, each part having a pair of symmetrically positioned channels provided with transversely extending ridges, the ridges in said part being in relative transversely offset positions, whereby when the said parts are assembled the ridges in the registering channels are disposed in longitudinally offset relation.

3. In an electrical attachment plug, a body portion formed of two like parts, each part having a pair of symmetrically positioned channels provided with transversely extending ridges, the ridges in said part being in relative transversely offset positions and the channels having depressions therein at the sides of the ridges, whereby when said parts are assembled the ridges in the registering channels are disposed in longitudinally offset relation and the depressions register with the ridges in the registering channels.

4. In an electrical attachment plug, a body portion formed of two like superposed parts, the meeting faces of said parts having registering recesses and registering channels therein, terminal members in said recesses, and flexible cords connected to said members and extending through the channels, the channels in each part having transverse ridges therein with the ridges offset transversely from each other and the channels further having depressions therein at the sides of said ridges, to register with the ridges of the registering channels when the two parts are assembled, whereby the ridges are adapted to depress portions of the flexible cords into the depressions and clamp the cords rigidly in the plug.

CHARLES F. SMITH.
